UNITED STATES PATENT OFFICE

163,682

COIN CONTROLLED FOOD DISPENSER

Harvey P. Curlee, Raleigh, N. C., assignor to Curlee Machinery Company, Inc., a corporation of North Carolina

Application June 13, 1950, Serial No. 10,503

Term of patent 14 years

(Cl. D52—3)

To all whom it may concern:

Be it known that I, Harvey P. Curlee, a citizen of the United States, residing at Raleigh, county of Wake, State of North Carolina, have invented a new, original, and ornamental Design for a Coin Controlled Food Dispenser, of which the following is a specification, reference being made to the accompanying drawing, forming a part thereof.

Fig. 1 is a plan view of a coin controlled food dispenser embodying my new design;

Fig. 2 is a front view thereof; and

Fig. 3 is a side view.

I claim:

The ornamental design for a coin controlled food dispenser, substantially as shown.

HARVEY P. CURLEE.
